UNITED STATES PATENT OFFICE

NICHOLAS DEAKIDES, OF ATHENS, GEORGIA

DESIGN FOR A TOY

Application filed September 18, 1930. Serial No. 37,014. Term of patent 3½ years.

To all whom it may concern:

Be it known that I, NICHOLAS DEAKIDES, a citizen of the United States, residing at Athens, in the county of Clarke and State of Georgia, have invented a new, original, and ornamental Design for Toy, of which the following is a specification, reference being had to the accompanying drawings, forming part thereof.

Fig. 1 is a perspective view showing my new design.

Fig. 2 is a top plan view.

Fig. 3 is a front elevation, and,

Fig. 4 is a side elevation.

I claim:—

The ornamental design for a toy, as shown.

NICHOLAS DEAKIDES.
